UNITED STATES PATENT OFFICE.

CHRESTIAN BURDAHL, OF MINNEAPOLIS, MINNESOTA.

PROTECTING-SHIELD.

1,181,289.

Specification of Letters Patent. Patented May 2, 1916.

Application filed September 11, 1915. Serial No. 50,263.

To all whom it may concern:

Be it known that I, CHRESTIAN BURDAHL, a subject of the King of Norway, residing at Minneapolis, in the county of Hennepin and State of Minnesota, have invented certain new and useful Improvements in Protecting-Shields, of which the following is a specification, reference being had to the accompanying drawings.

10 This invention relates to an improved protecting shield for use by soldiers in warfare and has for its primary object to provide a shield which may be easily rolled upon the ground by the soldier and will afford a complete protection to the body of the soldier when anchored in a stationary position, or when in motion.

The invention has for one of its more important objects to provide a rolling shield 20 for the above purpose, consisting of a circular metal plate of requisite thickness and diameter, and improved means for suspending a foot guard upon one side of the plate so that the same will not in any way interfere with the free rolling movement of the plate and will provide an auxiliary protector for the legs and feet of the soldier.

The invention has for a further object to provide a circular track mounted upon one 30 side of the shield plate, a hanger provided with a roller to travel on said track, the foot guard being pivoted upon the lower end of the hanger, and means for raising or lowering the foot guard or tilting the same so 35 that the guard will drag at one end upon the ground in the rolling movement of the shield, whereby a continuous travel of the hanger roller upon the track is assured and jerk or uneven motion eliminated.

40 It is another important object of the invention to provide improved anchors or supports for the rolling shield plate whereby the same may be firmly and rigidly set up in position upon the ground, and means 45 for mounting and securing said supports upon one side of the plate when the same is to be rolled or moved from place to place.

The invention has for a further general 50 object to provide a device of the above character which is of such construction that the same may be freely moved over a field by a troop of soldiers operating in unison against an enemy in the execution of military tactics, the shields being capable of very rapid 55 rolling movement in any desired direction.

With the above and other objects in view, my invention consists in the novel features of construction, combination and arrangement of parts to be hereinafter more fully described, claimed and illustrated in the accompanying drawings, in which,

Figure 1 is a side elevation illustrating the manner of using my improved rolling shield; Fig. 2 is a similar view thereof showing the shield in position to be rolled upon the ground; Fig. 3 is a front elevation of the shield; Fig. 4 is a rear elevation thereof; Fig. 5 is a similar view showing the foot guard adjusted to an inclined position; Fig. 6 is a rear elevation, the foot guard being shown in its effective position in full lines and in an elevated position in dotted lines; Fig. 7 is an enlarged rear elevation of the shield; Fig. 8 is a vertical diametrical sectional view; Fig. 9 is an enlarged side elevation with the shield set up in position for use; Fig. 10 is an enlarged front elevation; Fig. 11 is a detail elevation of the foot guard; Fig. 12 is a vertical section taken on the line 12-12 of Fig. 11; Figs. 13, 13^a 80 and 13^b respectively illustrate the sliding closure plate for the loop holes in plan, side elevation, and end views; Figs. 14 and 14^a are sections taken on the lines x-x and y-y respectively, of Fig. 7; Fig. 15 is an enlarged plan view with certain of the parts removed of the support on the shield plate for the standards or anchors; Fig. 16 is a detail sectional view taken on the line 16-16 of Fig. 7; Fig. 17 is a section taken on the line 17-17 of Fig. 7; Fig. 18 is a section taken at right angles to Fig. 17; Fig. 19 is an edge view of the hanger; Fig. 20 is a side elevation of the hanger; Fig. 21 is an edge view of the toothed quadrant; Fig. 22 95 is a side elevation thereof; Figs. 23 and 24 are sectional views taken on the lines 23-23 and 24-24 of Figs. 21 and 22 respectively; Fig. 25 is a detail elevation of the rack quadrant for holding the tilting lever; Fig. 26 is a sectional view thereof taken on the line 26-26 of Fig. 25; Fig. 27 is an end elevation of said plate; Fig. 28 is a diagrammatic view illustrating the manner in which the rolling shields are moved over a field by a 100 troop of soldiers in approaching an enemy.

In the accompanying drawings, I have illustrated what I believe to be the preferred embodiment of my invention, wherein 5 designates the rolling metal shield 110

plate which is of requisite thickness and diameter and at its outer edge and upon its rear face is formed with the laterally projecting annular flange 7 which affords additional strength at the perimeter of the shield 5 and a broader bearing contact surface with the ground. For the purpose of conveniently balancing the plate when rolling the shield upon the ground, I provide a horizontally disposed rod or shaft 9 which is rigidly fixed at one of its ends to the center of the shield plate by means of the nuts 10 having clamping engagement against the opposite faces of the plate. This rod projects rearwardly and is braced by means of a diametrically disposed bracket bar 11 which is riveted at its extremities to the plate 5. The medial portion of the bar 11 is disposed in parallel relation to the shield 10 plate and provided with a central opening therein through which the rod 9 extends. A second bracket bar 12, having a similar rod receiving opening, is disposed in a plane at right angles to the bar 11 and riveted to the 15 plate 5 at its ends. Between the bar 12 and the nut 10 which bears against the inner face of the plate 5, a metal sleeve 13 is arranged upon the rod 9 and securely fixed thereto by means of the set screw 14. This 20 sleeve is provided for the purpose of taking up longitudinal thrust upon the rod 9. In spaced relation to the bracket bar 11, a collar 15 is fixed upon the rod 9 by means of the set screw 16. A metal tube 17 is loosely 25 engaged upon the rod 9 and bears at its inner end against the collar 15. The sleeve 18 is exteriorly threaded upon the rear end of the tube. A washer plate 19 is engaged upon the threaded stud 20 projecting from 30 the end of the rod 9 and is tightly held against said rod and the end of the tube 17 by the nut 21. A metal thimble or bushing 22 is also engaged in the end of the sleeve 18 against said washer plate. The tube 17 35 revolves freely upon the rod 9 and, in operation, one soldier grasps said tube, holding it horizontally and thereby placing the shield plate in a vertical position while the other soldier turns the plate by grasping the circular track 23 to be later referred to, and exerting lateral pressure thereon. The shield thus turns or rolls over the ground 40 and, in proceeding as indicated in Fig. 28, the soldiers take turns rolling the shield 45 plate, thereby giving each man an opportunity to rest while balancing the shield. Upon the rear face of the plate 5 and in spaced relation thereto, a ring or annulus 50 23 is mounted in concentric relation to the shield plate. This ring is preferably supported by a plurality of bolts 24 mounted at one of their ends in the plate 5, and upon said bolts, between the ring 23 and the face of the plate 5, the spacing sleeves 55 25 are engaged.

26 designates a hanger which consists of an elongated metal plate having its upper end bent into U-shaped form, as indicated at 27. In this U-shaped bend of the hanger, a peripherally grooved roller 28 is journaled 70 upon a bolt 29. The groove in the periphery of the roller is of such width as to receive the inner edge of the ring 23. A Z-shaped bracket plate 30 is fixed to the hanger 26 at one of its ends and has its 75 other angular end portion engaged over the inner face of the ring 23 at the outer edge thereof, said bracket serving as a guide and preventing outward swinging movement of the hanger. The lower end portion of the hanger 26 is slightly increased in width and is formed with an upwardly projecting returned end portion 31. The end of a lever 32 is arranged between these spaced lower end portions of the 80 hanger plate and fulcrumed upon a bolt 33 fixed in the hanger. The particular purpose of this lever 32 will be hereinafter explained. In conjunction with the circular shield plate 5, I employ an auxiliary shield or 90 guard for the feet and legs of the soldier. This auxiliary guard consists of an elongated metal plate 34 which extends across the rear face of the plate 5 at its lower portion. The extremities of this plate 34 are of U-shaped form and provided with the spaced 95 upwardly projecting terminals 35 having laterally and inwardly extending arms 36 which project over the front face of the shield plate 5, as clearly shown in Fig. 10 of the drawings. A bolt 37 is engaged in the guard plate 34 at its center and adjacent the lower edge thereof, and upon said bolt the toothed quadrant 38 is mounted. This quadrant, shown in detail in Fig. 27 of the drawings, 100 is provided adjacent to its toothed edge with an arcuate slot 39 and also has a flange 40 formed upon its vertical edge. This flange is provided with oppositely projecting spaced lugs 41 arranged in pairs. A toothed quadrant 42, shown in Figs. 22 and 23, is also provided for the lever 32, said lever carrying the usual spring pressed dog 105 for engagement with the teeth of the quadrant. This quadrant 42 is also formed with a flange 43, said flange being provided with parallel longitudinally extending slots 44 and 45 respectively. Through the slot 45, the lever 32 extends, and in the slot 44 the lugs 41, projecting from one side of the flange 40 on the quadrant 38, are slidably 110 engaged. The hanger plate 26 is also formed upon one edge with a flange 46 which is disposed in parallel relation to the flange 43 and also has a longitudinal slot 47 formed 115 therein. This slot receives the oppositely projecting lugs 41 of the quadrant plate 38. In the guard plate 34 a bolt 48 is fixed at one of its ends and projects through the arcuate slot 39 in the plate 38 and also through an 120 125

opening provided in the lever 49 which is fulcrumed at one end upon the bolt 37. A rectangular guide plate 48' is engaged upon the bolt 48 and movable in the slot 39 and a second rectangular plate 48^a is also engaged upon the bolt between the lever 49 and the quadrant 38. This lever, of course, carries a locking dog for engagement with the teeth of the quadrant plate 38. The flange 40 of the quadrant 38 is provided with a slot or opening 50 through which the pivoted lever 32 extends. It will thus be seen that, by simply manipulating this lever 32 upon the quadrant 42, the guard plate 34 will be raised or lowered, as the lever 32 will bear against one of the end walls of the slot 50 in the flange of the quadrant 38 which is attached to said guard plate.

The guard plate 34, tending to gravitate downwardly and the sheave or roller 28 traveling freely upon the track 23, causes the roller to at all times maintain a position on the lowest point of said track. If the sheave were thus permitted to travel freely upon a circular track in the rolling movement of the shield plate, the shield, upon being turned, would cause the sheave or roller to move upon the track in a series of jerky motions, thereby tending to bind the foot guard so that it would be carried around with the shield. In order to overcome this binding strain, I have provided the pivoted lever 49 which is connected at a medial point to the guard plate 34 in the manner above stated.

When this lever is moved in either direction from a central position with respect to the slot 39 in the quadrant plate, the foot guard will be tilted and thrown off balance, as indicated in dotted lines in Fig. 4 so that there will be a greater weight at one end of the guard than at the other, in accordance with the direction of travel of the rolling shield. This tilting of the foot guard causes the lower end to drag slightly upon the ground, whereby, in the continued turning movement of the shield, this dragging weight will force the sheave or roller 28 upwardly upon the curved track. The roller being thus moved off center and placed upon an incline, will immediately gravitate downwardly upon the track back to its central position. This action is constantly repeated in the rolling movement of the shield. As the foot guard drags at one end upon the ground, its downward movement will be retarded and regulated, thereby causing the sheave or roller to travel at an even speed upon the track corresponding to the rolling speed of the shield. When the shield is moved up or down an incline, the guard is further tilted, as indicated in Fig. 5, so that it is disposed in approximately parallel relation to the ground surface, and when the shield is rolled over uneven or broken ground, the foot guard will be elevated as in Fig. 6, by the manipulation of the lever 32. When it is desired to set up the shield in a stationary position, the lever 32 is operated to lower the foot guard so that its lower edge will contact firmly with the ground and provide a complete shield and protection from rifle bullets for the legs and feet of the soldiers stationed behind the shield.

For the purpose of rigidly supporting or anchoring the shield in a vertically inclined plane, as shown in Fig. 1, I provide the detachable supports or standards 51, each of which consists of an angle bar terminating at one end in an angularly disposed pointed foot plate 52 which is adapted to be securely embedded in the ground. The other end of each angle bar is provided with a metal block 53 of rectangular form, from the opposite faces of which spaced studs 54 project. In the shield plate 5, above its center and on opposite sides thereof adjacent the flange 7, rectangular openings 55 are provided. Through these openings, the ends of the supporting standards carrying the blocks 53, are engaged, and the lugs 54 disposed against the opposite faces of the shield plate. The standards 51 are then disposed at the desired inclination and forced inwardly toward each other, causing the same to bind against the opposite edges of the openings 55 and the tapering foot plates 52 are then forced into the ground. Thus, the circular shield plate will be rigidly supported in a stationary position. I have also devised very simple and convenient means on the rear face of the shield plate 5, upon which the detachable standards 51 may be mounted and secured to be carried by said plate as it is rolled over the ground. To this end, a pair of parallel bars 56 is riveted as at 57, to the medial portion of the brace bar 11 on opposite sides of the rod 9, and extend at right angles to said brace bar. The extremities of these bars 56 are secured to the rear ends of bolts 58 fixed in the shield plate 5, and metal sleeves 59 are arranged upon said bolts between the bars 56 and the rear face of the shield plate. Upon the ends of the bolts 58 which are disposed through corresponding ends of the parallel plates 56, a plate 60 is engaged and tightly secured by means of the nuts 61. Each of the plates 60 is centrally provided with a hollow cylindrical boss 62 and one end of the plate 60 is angularly formed and, to the same, a hasp member 63 is hingedly connected, as indicated at 64. This hasp member is provided with an angular substantially U-shaped portion 65 to accommodate the boss 62, and in this medial portion of the hasp a rectangular opening 66 is formed to receive a head 67 of similar shape on one end of a bolt 68 which extends axially through the boss 62 and an opening in the plate 60. The hasp member 65 also has openings 69 formed

therein to receive the ends of the bolts 58. After the supporting standards 51 are detached from the shield plate, they are arranged upon opposite sides of the boss 62 on 5 the spaced plates 60, and one flange of each of the angle bars is provided with openings 70 to receive the ends of the bolts 58. The hasp member 65 is now swung to its closed position, after which the bolt 68 is turned 10 to dispose the head 67 thereon at right angles to the slot 66. A nut 71, threaded upon the opposite end of this bolt, is then tightened against the face of the plate 60. It will thus be seen that, by the provision of these 15 two fastening devices arranged on opposite sides of the central rod 9, the standards 51 will be securely held upon the plate 5 as it is rolled over the ground.

72 designates spaced rectangular loop 20 holes which are cut in the shield plate 5 at one side of its center, and when the shield is mounted in a stationary position for use, as in Fig. 9, these loop holes will be above the center of the plate. Upon the rear face of 25 the plate 5, the obliquely disposed parallel lips 73 are integrally formed, one of said lips being located on each side of the loop holes 72. These lips constitute guides for 30 a closure plate 74, the opposite edges of which are rabbeted, as at 75. The lips 73 are provided with undercut grooves 76 to receive the rabbeted edges of the closure plate. Each of the lips 73 is also increased in width intermediate of its ends to provide 35 a flange 77 which overhangs the body of the closure plate. The flange 77 on one of the lips is provided with spaced notches 78. Upon the face of the closure plate 74, spaced lugs 79 are formed, each of said lugs being 40 bored to loosely receive the opposite ends of a locking pin 80. This pin is provided with a suitable finger piece 81 and a coil spring 82 is arranged upon the pin between said finger piece and one of the lugs 79. This 45 spring normally acts to project the pin 80 through the other of the lugs and into one of the sockets 78 in the guide lip. In Fig. 7 of the drawings, I have shown the closure plate on the left hand side of the shield in 50 its open position while, on the right hand side of the shield, the plate is shown in closed position over the loop hole 72. By simply releasing the locking pin 80, the plate 74 may be easily and quickly shifted in 55 either direction to open or close the loop holes.

From the above description of the construction of my improved rolling shield, it will be apparent that there is no impediment 60 whatever to the free rolling movement of the circular shield plate while, at the same time, a very efficient auxiliary guard device for the feet and legs of the soldier is provided and permanently connected to the guard plate in such manner

as to at all times maintain its pendant position with relation to said plate.

In Fig. 28 of the drawings, I have disclosed one desirable manner of moving the shields by a troop of soldiers across a field in a military maneuver. In this figure I have illustrated an enemy trench at T which is protected at some distance in advance thereof by the wire entanglements W. At the bottom of the sheet, I have shown a series of the rolling shields S, each of which is operated by two soldiers, the diagram being thus indicative of an attacking force upon the trench. By spacing the shields apart and dividing the attackers into columns of two relays, each making short advances alternately, the attackers are afforded an opportunity of killing any reckless trenchman who may expose himself, and at the same time the men may obtain a period of rest from their efforts in rolling the shield. When the foremost line of shields is advanced to where they are safely beyond bomb throwing distance from the trench, as indicated by the line of shields S', they stop momentarily and send out men at different points along the line to cut the wire entanglements W, the remainder of the men in the line keeping up a steady fire to prevent bomb throwers interfering with the wire cutting operations. This lining up of the advancing troop gives the men an opportunity to rest for the final dash against a trench, which will occur after the wires have been cut. It is, of course, understood that, when the shields are brought up to the advanced position, hand grenades, bombs, or other projectiles are supplied to the troops. With the wire entanglements cut, the shields are rolled forward toward the trench, the men moving alternately in diagonal lines and scattering as much as possible so as to afford the men in the rear an opportunity of firing. With the use of bombs and a constant rifle fire from behind the shields, the shields are advanced to the very front edge of the trench so that the complete success of the attack is assured and with a minimum of loss of life among the attacking troops. If the enemy in the trench should succeed in getting a partial side view of the men back of the shields, he would have to get up to a certain height, and in getting to such position so that he could fire upon the attackers, he would himself be dangerously exposed.

It will thus be seen that my improved shield provides a complete and effective protection for the attacking troops and, as the shields will freely roll over the ground with great speed after being once started, they will place no material additional burden upon the soldiers in advancing upon the enemy.

From the foregoing description, it is be-

lieved that the present invention will be fully and thoroughly understood.

The device as a whole is comparatively simple in its construction and the several elements thereof may be manufactured and assembled in the complete device at relatively small cost. As indicated in Figs. 1, 2 and 3 of the drawings, the metal shield plate 5 is preferably of such diameter that it will completely shield a man of average height when in a kneeling position. The rifle loop holes provided in the shield plate are of such size as to enable the rifle to be readily inserted therethrough and give sufficient clearance space so that the sight may be drawn along the rifle barrel. The barrel can also be readily disposed at various angles through the loop holes. The track 23, in addition to constituting a support for the hanger 26, also serves as a convenient hand hold whereby the rolling shield plate may be propelled over the ground.

While I have shown and described the preferred construction and arrangement of the several features of my invention, it is to be understood that the device is, nevertheless, susceptible of considerable modification therein and I, therefore, reserve the privilege of adopting all such legitimate changes as may be fairly embodied within the spirit and scope of the invention as claimed.

Having thus fully described my invention, what I desire to claim and secure by Letters Patent is:—

1. A circular metal shield plate adapted to be rolled upon the ground, and a pendant foot guard mounted upon one side of said plate.
2. A circular metal shield plate adapted to be rolled upon the ground, a pendant foot guard mounted upon one side of said plate, and means for vertically adjusting said foot guard with respect to the shield plate.
3. A circular metal shield plate, balancing means centrally connected to the plate, said plate being provided with spaced loop holes, means for supporting the plate in a stationary position upon the ground, and means on said plate upon which said supporting means is adapted to be mounted and carried with the plate when the latter is rolled.
4. A circular metal shield plate adapted to be rolled upon the ground, a pendant foot guard mounted upon one side of said plate, and means for positioning the foot guard at an oblique angle with respect to the shield plate.
5. A circular metal shield plate adapted to be rolled upon the ground, a pendant foot guard mounted upon one side of said plate, means for positioning the foot guard at an oblique angle with respect to the shield plate, and additional means for vertically adjusting the foot guard with respect to the shield plate.
6. A circular shield plate provided upon its outer edge with a ground engaging flange, balancing means centrally connected to said plate, detachable supports adapted to be operatively connected at one of their ends to said plate and anchored at their other ends in the ground, and means carried by the shield plate in which said detachable supports are adapted to be mounted to be carried by the plate in its rolling movement.
7. A circular shield plate provided with means for rolling the same upon the ground, and a suspended foot guard mounted upon one face of said plate and adapted for engagement with the ground surface when the plate is stationary.
8. A circular shield plate provided with means for rolling the same upon the ground, a suspended foot guard mounted upon one face of said plate and adapted for engagement with the ground surface when the plate is stationary, and detachable supports adapted to be connected to said plate at one of their ends and embedded in the ground at their opposite ends.
9. A circular metal shield plate provided with means for balancing the same, an annular track mounted upon one face of said plate and affording means for rolling the plate, and a foot guard suspended from said track to maintain a substantially stationary position when the plate is rolled over the ground.
10. A circular metal shield plate provided with means for balancing the same, an annular track mounted upon one face of said plate and affording means for rolling the plate, a foot guard suspended from said track to maintain a substantially stationary position when the plate is rolled over the ground, and means for lowering said foot guard into bearing engagement with the ground surface or elevating the same out of contact therewith.
11. A circular metal shield plate provided with means for balancing the same, a track mounted upon one face of the shield plate and affording means for rolling the plate, a hanger suspended from said track, a foot guard mounted upon the lower end of the hanger, and means for adjusting said foot guard with respect to the hanger.
12. A circular metal shield plate provided with means for balancing the same, a track mounted upon one face of the shield plate and affording means for rolling the plate, a hanger suspended from said track, a foot guard mounted upon the lower end of the hanger, and means for disposing the foot guard in a horizontally inclined plane with respect to the hanger.
13. A circular metal shield plate provided with means for balancing the same, a track

mounted upon one face of the shield plate and affording means for rolling the plate, a hanger suspended from said track, a foot guard, and means for adjustably positioning 5 the foot guard upon the hanger to cause one end of the guard to drag upon the ground as the shield plate is rolled, whereby the hanger is moved with respect to the track and caused to gravitate downwardly thereon 10 to its normal position.

14. A circular metal shield plate provided with means for balancing the same, an annular track mounted upon one face of said plate and affording means for rolling the 15 plate, a hanger provided with a roller to travel upon said track, a foot guard, a plate carried by said guard, and a lever mounted upon the hanger and co-operatively engaging said plate to raise or lower the foot guard 20 with respect to the ground surface.

15. A circular metal shield plate, an annular track mounted upon one face of said shield plate affording means for rolling said plate, a hanger provided with a roller to travel 25 upon said track, a foot guard, a plate upon which said foot guard is pivotally mounted, a lever fulcrumed upon the hanger and co-operatively engaged with said plate to raise or lower the foot guard, and a second lever 30 connected to said foot guard to tilt the same to a horizontally inclined position with respect to the hanger.

16. A circular metal shield plate, an annular track mounted upon one face of said 35 shield plate affording means for rolling said plate, a hanger provided with a roller to travel upon said track, a foot guard, manually operable means mounted on the hanger and co-operatively engaging means on the 40 foot guard to raise or lower the latter, and additional manually operable means to tilt the foot guard and dispose the same in a horizontally inclined position with respect to the hanger.

45 17. A circular metal shield plate provided with means for rolling the same over the ground, and a foot guard permanently carried by said plate and operatively connected thereto by means which will maintain the 50 foot guard in a substantially constant position with respect to the shield plate as the latter is rolled over the ground.

18. A circular metal shield plate provided with balancing means, an annular track 55 mounted upon one face of said shield plate, a hanger provided with a grooved roller to travel upon said track, a quadrant vertically slidable upon the hanger, a foot guard pivoted intermediate of its ends upon the quadrant, and a manually operable lever pivotally mounted upon the hanger and co-acting with the quadrant to shift the same upon the hanger and raise or lower the foot guard. 60

19. A circular metal shield plate provided

with balancing means, an annular track 65 mounted upon one face of said shield plate, a hanger provided with a grooved roller to travel upon said track, a quadrant vertically slidable upon the hanger, a foot guard pivoted intermediate of its ends upon the quadrant, a manually operable lever pivotally mounted upon the hanger and co-acting with the quadrant to shift the same upon the hanger and raise or lower the foot guard, 70 said quadrant being provided with an arcuate slot, a second manually operable lever fulcrumed at one end and adapted to be locked in adjusted position upon the quadrant, and a bolt fixed in the foot guard movable in said slot and connected to said 80 lever whereby said foot guard may be disposed in a horizontally inclined position with respect to the hanger.

20. A circular metal shield plate provided with means for rolling the same over the 85 ground, said shield plate being provided at opposite points adjacent its outer edge with rectangular openings, and supporting standards adapted to be detachably engaged through said openings at one of their ends 90 for binding engagement with the opposite edges of the openings, said standards being provided with spaced lugs for frictional contact against opposite faces of the shield plate and the opposite ends of the standards 95 terminating in pointed feet to be embedded in the ground.

21. A circular metal shield plate provided with means for rolling the same over the ground, detachable supports adapted to be 100 connected to the shield plate at one of their ends and engaged in the ground at their other ends, bolts fixed at one of their ends in the shield plate, said supports being provided with openings to receive said bolts, 105 and hinged clamping members mounted upon the bolts and embracing said supports when arranged upon the bolts to clamp the supports in position for movement with the shield plate when the latter is rolled upon 110 the ground.

22. A circular metal shield plate, an annular track mounted upon one face of said plate and affording means for rolling the plate over the ground, and a foot guard suspended from said track to maintain a substantially stationary position in the rolling movement of the plate. 115

23. A circular metal shield plate adapted to be rolled upon the ground, a foot guard 120 mounted upon one side of said plate, and means for adjusting said foot guard to position the same with respect to the edge of the shield plate.

24. A circular metal shield plate adapted 125 to be rolled upon the ground, a foot guard, means for mounting said guard upon one side of the shield plate whereby the guard

will maintain a substantially constant position with respect to the plate during the rolling movement of the latter.

25. A circular metal shield plate adapted to be rolled upon the ground, a hanger, means for suspending said hanger from the shield plate whereby the hanger will maintain a substantially constant vertical posi-

tion during the rolling movement of the plate, a foot guard mounted upon said hanger, and means for adjusting the foot guard with respect to the hanger and the shield plate. 10

In testimony whereof I hereunto affix my signature.

CHRISTIAN BURDAHL.

Copies of this patent may be obtained for five cents each, by addressing the "Commissioner of Patents, Washington, D. C."
